(No Model.)

J. S. STERRETT.

AUTOMATIC CAR BRAKE.

No. 360,062.

Patented Mar. 29, 1887.

UNITED STATES PATENT OFFICE.

JACOB S. STERRETT, OF PHILADELPHIA, PENNSYLVANIA.

AUTOMATIC CAR-BRAKE.

SPECIFICATION forming part of Letters Patent No. 360,062, dated March 29, 1887.

Application filed August 19, 1886. Serial No. 211,358. (No model.)

To all whom it may concern:

Be it known that I, JACOB S. STERRETT, a citizen of the United States, and a resident of Philadelphia, Pennsylvania, have invented 5 certain new and useful Improvements in Automatic Car-Brakes, of which the following is a full, clear, and exact description, reference being had to the annexed drawings, making part hereof.

10 The nature of my invention will fully appear from the following specification and claims.

In the drawings, Figure 1 is a plan view of the operative parts of my device to be attached beneath a car; Fig. 2, an end view of a car-15 platform, showing the brake-handle, reversing-lever, and buffer; Fig. 3, an elevation of a car-truck, showing the brake attachment. Fig. 4 shows detached views of parts of the reversing mechanism; Fig. 5, a detached view of 20 the brake-bar and springs to graduate the pressure of the brakes; Fig. 6, a detached view of the pivoted brake-lever and its supporting-frame; Fig. 7, a broken view showing the under side of one of the heads of the push 25 and draw bars connected with the pivoted brake-lever; Fig. 8, a perspective view of the reversing mechanism.

A, Fig. 1, is the combined buffer and coupler; B B, bars for sustaining the spiral springs 30 B' B' between the two cross-heads C C'; and D D, a push-bar provided with the frame D', the office of which latter is simply to carry this bar around the pivot which secures the truck to the car.

35 E E are supports attached to the bottom of the car, and embrace and suspend the push-bar D.

F is a cross-head secured rigidly at its middle to the end of push-bar D, its ends clasping 40 loosely the push-rod G and draw-rod G'.

H H' is a short double lever, pivoted in the middle and suspended from the bottom of the car by the hanging frame K. (See Figs. 1 and 6.) This lever is rigidly attached upon the 45 upright bar or shaft K'. To the lower end of this shaft K is rigidly pivoted the long lever L L'. To one end, L, of this long lever is attached the brake-bar J. The outer end of this brake-bar is attached to the brake-lever L'', Fig. 3. The other end, L', of the long lever is attached to rod I by a hinge-joint, rod I terminating in a chain which may be wound

upon brake-handle I' (see Fig. 2) in the usual way.

M M are two collars loosely fitting around 55 bar G, and are backed up by a collar, M'', rigidly set on bar G.

N is a short lever-arm projecting from collar M, and hinged by a rod, N', to a short lever N'', which in its turn is secured rigidly to bar 60 O. The latter at its outer end is rigidly attached to a lever, O', at the front of the platform. (See Figs. 1, 2, and 8.) Collar M is pierced with two holes, which receive the lugs O'' O''' from collar M'. (See Figs. 4 and 8.) 65 These lugs, being of greater length than collar M, will project through the latter, as shown in Figs. 1 and 8.

P and P' are two loose collars on bar or rod G', and are backed up by collar P'', which is 70 rigidly secured to the forward end of bar G'. Collar P is provided with a short lever, Q, which is joined by connecting-link Q' with lever Q'', the latter being connected rigidly with bar O. Collar P is pierced with two holes 75 similarly to collar M, which receive loosely the two lugs R R'. The lugs R R' are adapted to be set against one side of cross-bar F, while lugs O'' O''' are adapted to be set against the opposite side of this bar. (See Figs. 1 and 8.) 80 Bar F is moved forward and backward by the draw and push of rod D. Rods G and G' are slotted, as shown in Fig. 7, at their points of attachment to lever H H'. The connecting-pins move in the slots and permit free movement of the lever H H'.

S is the brake-beam bearing the brake-shoes S' S'', (see Fig. 5,) and is provided with spiral springs T T, set between bar T' and the brake-beam. These springs act as cushions to graduate the force or shock of closing the brakes. 90

The operation of the device is automatic, and is as follows, viz: As the cars of the train come together upon stopping, each buffer A is forced in, and bar D is pushed backward, 95 thus forcing the bar F against lugs O'' O'''. This will drive the lugs backward and force collar M' against tight collar M'', moving rod G back and forcing the ends H and L of the rear levers back, thus pulling on rod J and lever L'' and closing the brakes. As the train starts, the pressure will be released from lugs O'' O''', and the brakes will free themselves. If it is desired to close the brakes when back-

ing, the operation is effected by a sudden stoppage, which throws the cars apart and causes a pull on buffer A. Previously to backing, however, it is necessary to reverse lever O', thus partially turning rod O, and, by means of levers Q Q", throwing collars P P' around until the lugs R R' are turned to a position opposite to one face of the bar F, as the lugs O" O'" are shown to be in Fig. 8. By 5 to the turning of rod O the lugs O" O'" are thrown out of line with bar F by levers N N". Now, as the train in backing comes to a stop, the buffer A is drawn out and the pull draws on rod D D and bar F, and the latter pushes 10 15 against lugs R R', thus drawing on lever G' and the H' and L' ends of the two rear levers so lettered. This will force back the opposite ends of these levers and draw on rod J, closing the brakes, as before. After the train has 20 come to a stop and the brakes are applied, they can be instantly released and prepared for a reverse movement by reversing lever O', thus freeing the lugs of the collar mechanism, which the bar F has just operated on from the 25 pressure of this bar F. This movement will free the brakes.

On the stopping of the engine drawing the train the buffer will be pressed into its utmost limit, partially compressing the springs, and the 30 only pressure exerted on the brake-shoes will be the force contained in the springs so compressed. It will be observed, therefore, that the whole force exerted to close the brakes is yielding pressure. I am well aware that springs 35 have been heretofore used to graduate the first shock of putting on the brakes where the resultant effective force of closing them was

positive; but none of the devices heretofore used have shown a resultant yielding pressure upon the brake-shoes. In my device the 40 springs not only break the first shock referred to, but continue the elastic pressure.

What I claim as new is—

1. In an automatic brake mechanism, the combination of buffer A, rod D, and cross-bar 45 F, the latter being adapted to be drawn back and forth by the inward push or outward draw from the buffer, and connected by levers with the brake mechanism L to close the brake-shoes against the wheels, substantially as described. 50

2. In an automatic brake mechanism, the combination of buffer A, rod D, cross-bar F, the latter being adapted to be drawn back and forth by the push and draw of the buffer and moving upon rods G G', the latter being 55 hinged to the lever H H' to move brake-rod J back and forth, collars M M' M" and P P' P", set upon said rods and provided with lugs O" and R, the whole arranged and operating substantially as described.

3. In an automatic brake mechanism, the combination of buffer A, rod D, cross-bar F, the latter adapted to be drawn backward and forward by the action of the buffer, and mounted on rods G G', the latter being hinged to the 60 lever H H' to move brake-rod J, collars M M' M" and P P' P", set upon said rods and provided with lugs O" and R, levers N N" and Q Q", and rod O, connected and arranged substantially as and for the purposes described.

JACOB S. STERRETT.
